PAN UNIT

Elmer H. Chandonia, Amelia, Ohio, assignor to
The Lockwood Manufacturing Company, Cincinnati, Ohio, a corporation of Ohio

Application April 7, 1937, Serial No. 135,415

3 Claims. (Cl. 53—6)

This invention relates to improvements in a pan unit of the general character disclosed in a patent, No. 2,037,759, granted to me on April 21, 1936, and disclosing a novel strap connection for the pans.

An object of the present invention is to improve upon the strap connection disclosed in my granted patent, above mentioned, and to facilitate assembly of the pans and straps into units.

Another object of the invention is to impart additional strength and durability to the connections between the straps and pans, and to locate the connections as close as possible to the pan corners, thereby to minimize the tendency of the pans to rock about their mountings upon the straps and to prevent harmful looseness of the connections.

A further object is to secure as nearly as is possible, a positive and permanent connection between the straps and the pans.

The foregoing and other objects are attained by the means described herein and disclosed in the accompanying drawing, in which:

Fig. 1 is a fragmental elevational view of a side of a bake pan unit embodying the invention.

Fig. 2 illustrates an intermediate step in the operation of securing the connecting straps to the bake pans.

Fig. 3 is an enlarged cross-sectional view taken on line 3—3 of Fig. 1.

Fig. 4 is a fragmental perspective view of one corner of a bake pan, as seen from an end of the pan, showing the fold structure.

As is customary, the pan unit comprises a series of bake pans 4 held in connected relationship by means of a connecting strap 5 formed, usually, of a suitable heavy gauge metal. Each pan of the unit is fabricated by folding a sheet metal blank at its corners, and along marginal portions of its edges, to provide integral sides, ends, and a bottom. The upper edges of the sides and ends may be finished in any acceptable manner, such as by turning said edges to form lips 8, and these lips may be re-enforced by a wire 9, if desired.

The end folds 6 and 7 resulting from formation of the pans, are distinguished from the corresponding folds 6 of the device shown in Patent No. 2,037,759, in that they are not triangular. The finished folds are rather of trapezoidal formation generally, and having substantially a vertical irregular or serrated edge beginning at the point 12 and extending upwardly toward the lip 8. The irregularities or serrations of the substantially vertical edge are such as to provide

opposed pockets or notches 13 and 14 in the folds of the pan ends. These pockets or notches are adapted to receive lugs of the connecting strap, as will be explained presently, and each has a lower abutment edge 15, an upper abutment edge 16, and a bottom or base edge 17.

The metal connecting strap 5 which embraces the group of pans may be formed with a beaded edge 18 which is adapted to be positioned adjacent to the lips 8 of the pans. Adjacent to the end of each pan, the strap 5 is provided with a pair of oppositely directed lugs 19 and 20 each of which extends rearwardly of strap 5 from the apertures 21 and 22, respectively, provided in strap 5. Said apertures result from the striking out of the respective lugs so that the vertical width of each aperture is materially greater than the vertical width of its associated lug. The horizontal distance between the bases 23 and 24 of lugs 19 and 20 is approximately the same as the horizontal distance between the bottom edges or bases 17 of the pockets of the end flaps 6 and 7.

In the process of forming the pans from the blanks as previously stated, the end flaps or folds 6 and 7 will be pressed against the end of the pan, thereby making it almost impossible to insert the strap lugs beneath said flaps. It is therefore necessary to raise the inner edges of the flaps and this may be accomplished by subjecting the pans to a press having a blade which when actuated lifts up the inner edges of said flaps a distance sufficient to permit the insertion of the lugs. The lugs are then introduced beneath the flaps of the pan near the bottom, (see Fig. 2), and having been thus positioned, the strap is moved vertically along the pan ends as far as it will go. The free vertical movement of the strap will be terminated when the bases 23 and 24 of lugs 19 and 20 come into contact with the lower edges of wings 25 and 26 which form the lower side 15 of the pockets. In order to continue the vertical movement of the connecting strap 5 to its final position, an external force is necessary to force the bases 23 and 24 of the lugs over the wings 25 and 26. This operation may be done by a machine press. As the strap is forced into position so that beaded edge 18 abuts lip 8 of the pan and so the lugs are positioned in their respective pockets, the wings 25 and 26 are distorted outwardly following the contour of the bases 23 and 24 of the lugs 19 and 20.

The final machine operation is that of applying great pressure to the abutting surfaces of the pan and connecting strap. This application of pressure bends the lugs 19 and 20 toward their mounting strap 5.

thereby forcing portions of the pan metal at the pockets into the apertures 21 and 22 of the strap. The pressure also forces the metal of the folds or flaps into close engagement with each lug, and 5 flattens the previously distorted wing flaps 25 and 26 back to their original position. The final position of the lug, pocket, strap, pan end and wing is shown in Figs. 1 and 3. It is seen that in this manner the individual pans are permanently locked to the metal connecting strap 5.

An outstanding advantage of the present invention is the attainment of a superior and effective anchorage or permanent lock arrangement 10 gotten by forcing the folds of the pocket of the 15 end flaps of the pan into the apertures around the lugs and also by providing a bearing surface 15 to positively support the lug from its lower side. The practical advantage of this bearing support 15 lies in the additional reinforcement 20 and strength added to the unit, especially valuable when, through use and abuse, the crimp fit between the side flaps of the pan and co-crimped lugs of the straps may become somewhat loosened. However, since the horizontal distance between 25 the bottom edges of a pair of pockets is approximately equal to that between the base support edges of the corresponding pair of lugs, the strap is held in place and cannot slide down and out from under the end flaps of a pan because of the 30 retaining function of the bearing surface 15 of the wings. This reinforcement is equal in amount to the shear strength of the metallic wings 15.

By eliminating the conventional triangular formation of the folds 6 and 7, and providing the 35 substantially vertically inclined edges beginning at the locations 12, I am enabled to secure a substantial increase in the distance between the strap lugs, which results in locating the strap connections much closer to the pan corners than 40 has been possible heretofore. It will at once be appreciated that this greater spacing of the connections between the strap lugs and the end folds of the pan, materially lessens the liability of the pan to tilt or become cocked in relation to the 45 connecting strap. The resultant increase of strength at such locations, coupled with the locking function of the abutment wings 15 upon the strap lugs, provides an improved pan unit of unusual durability.

It should be understood that the connecting strap may be of one-piece construction, encircling any reasonable number of grouped pans, or, if desired, it may be made up of appropriate sections joined together or fastened to bumper elements or protective plates on the ends of the 55 units, all in accordance with common practice. These and other modifications such as may fall within the scope of the appended claims, are to be understood as being comprehended in the formation of completed pan units of various styles and sizes.

The size of the openings 21 and 22 are preferably such that when the lugs 19 and 20 are operated upon for returning same toward those openings, those openings will substantially be filled with the sheet metal of the pan that is forced into those openings. It is obvious that in those instances where two plies of sheet metal of the pan are together somewhat thinner than the 60 thickness of the strapping 5, some portions of the lugs 19 and 20 may also enter the openings 21 and 22, rather than that the lugs be disposed wholly in back of the strapping as shown in Fig. 3.

The operation of lifting the foreshortened inner 75 edges of the folds or flaps for facilitating entry

of the lugs 19 and 20 into the opposed pair of pockets 13 and 14 of any pan, serves to temporarily increase the distance between the bases 17 of such pockets, thereby permitting the assembly 5 of the lugs and pockets with little or no distortion of the sheet metal of the pan flaps which extends downwardly from pockets. Any slight distortion of such sheet metal is rectified by the next operation which flattens such distorted metal. The strapping in the finished article extends over any 10 such metal as may have been distorted and consequently protection is provided against any physical injury to workmen should it ever occur that any sharp edges are developed incident to the indicated assembly operation.

It is to be understood that it is not intended to limit the creation of units as explained herein to the exact method of production explained herein. It is obvious that the flaps 6 and 7, as initially formed, may be permitted to extend from 20 the body portion of the pan and thus obviate the herein explained step of lifting those flaps preparatory to insertion of the lugs in the pockets.

In actual use, it is to be anticipated that by reason of the impact of assembled pan sets, some 25 of the pans may become somewhat loose, however, under such circumstances the pocket walls serve as abutments that effectively prevent separation of the pans from the strapping.

It is also within the purview of this invention, 30 that there may be occasion to have a relatively loose association of a plurality of pans with strapping, so each pan may be substantially self-nesting or seating on the oven floor. This is readily attainable by the means disclosed herein, by so 35 proportioning the pockets and lugs, that the desired or necessary degree of looseness or rocking may be established between the individual pans and the strapping, yet utilizing the interlocking 40 relationship of such pockets and lugs for preventing separation of the pans from their associated strapping.

It is to be understood that a pair of oppositely directed or extending lugs 19 and 20 are to be provided for each end of each pan assembled 45 in the frame established by the strapping 5, and which strapping ordinarily encircles or provides a peripheral band for the various pans secured together in a multiple pan assembly.

As shown herein, the opposed wings 25 and 26 50 are spaced apart a distance slightly greater than the spacing of the opposed flap portions disposed above the pockets 13 and 14. This gives a slightly larger bearing or abutment face between the upper edges of the lugs and the pockets, and consequently serves to provide a firm grip on the strapping between the upper pocket walls and the under edge of the lip 8 of the individual pans. Such arrangement does not interfere with the opposed or registering positions of the mouths of 55 the pockets provided at the end of any pan and which mouths are substantially aligned horizontally when a pan assembly is placed in normal position for securing charges of dough preparatory to baking thereof.

It should be noted that the end folds, adjacent the pockets and adjacent the openings in the strapping, are deformed incident to pressing such fold material into such openings, and thus there are formed recesses in the material of the 60 fold and which recesses serve as pockets in which the lugs are disposed in the assembled device.

What is claimed is:

1. The combination of a bake pan having end folds each provided with a pocket, the pockets 75

each having upper and lower walls, a bottom and a mouth and each of said mouths opening toward the other and a strap having a pair of spaced lugs formed therefrom whereby to provide openings 5 in the strap, the lugs projecting away from one another and toward opposite ends of the strap, the lugs being attached to the strap at a distance apart approximating the spacing of the bottoms of said pockets, the lugs being received in said 10 pockets and the end folds, about said pockets, being deformed so as to lie within the openings in the strap.

2. The combination of a bake pan having end 15 folds each provided with a pocket, the pockets each having upper and lower walls, a bottom and a mouth and each of said mouths opening toward the other and a strap having a pair of spaced lugs formed therefrom whereby to provide openings in the strap, the lugs projecting away from 20 one another and toward opposite ends of the strap, the lugs being attached to the strap at a

distance apart approximating the spacing of the bottoms of said pockets, the lugs being received in said pockets and the end folds, about said pockets, being deformed so as to lie within the openings in the strap, and the lugs being seated in 5 the deformed portions of the folds.

3. In a multiple pan structure of the class described, the combination of a plurality of spaced 10 bake pans, each pan having end folds each provided with a pocket, the pockets of the folds at 15 the same end of each pan opening toward one another and strapping disposed at the opposite ends of the pans and having lugs spaced from one another at the approximate distance between the pockets and extending into the pockets, 15 whereby contact of the side walls of the pockets and the side edges of the lugs locks the pans and strapping together and restrains the pans and strapping against relative vertical separating movement. 20
